UNITED STATES PATENT OFFICE.

ALBERT NOYES, OF ATLANTA, GEORGIA, ASSIGNOR TO AMERICAN BAG COMPANY, OF MEMPHIS, TENNESSEE, A CORPORATION OF TENNESSEE.

BAG-TURNING MACHINE.

1,148,853.

Specification of Letters Patent. Patented Aug. 3, 1915.

Application filed April 1, 1915. Serial No. 18,515.

To all whom it may concern:

Be it known that I, ALBERT NOYES, a citizen of the United States, residing at Atlanta, in the county of Fulton and State of Georgia, have invented certain new and useful Improvements in Bag-Turning Machines, of which the following is a specification.

This invention relates more particularly to improvements in that class of bag turning machines in which the bags are turned by air suction, and in order to more fully describe the same, reference will be had to the accompanying drawings which show one specific form of a machine embodying said invention, and wherein:

Figure 1, is a side elevation of said machine; Fig. 2, a top plan view thereof with the superstructure removed; Fig. 3, a central vertical section of the suction chamber with the two sections thereof separated; Fig. 4, a section on line 4^x—4^x Fig. 1, and Fig. 5, a detail end elevation of the expandable mouth through which the bags are drawn.

The machine herein shown comprises, among other parts, an air suction chamber which is made in two separable sections 1 and 2. Section 1 is mounted fast upon the top of the main frame 3 of the machine, while section 2 is adapted to reciprocate in front of section 1, and for this purpose is slidably mounted in stationary guides 4. Section 1 is provided with two air passages or compartments 5 and 6. Compartment 5 is provided with an air outlet 7 for attachment to a duct 8 which leads to a suction fan 9 or any other means for producing air suction through the outlet 7 in the direction indicated by the arrows in Fig. 3. Compartment 5 is closed at one end where it is provided with a glass window 10 and is open at its opposite end. Compartment 6 is provided with a telescoping section 11, which is adjustable longitudinally of said compartment for different lengths of bags. This adjustable section 11 is provided with an expandable mouth consisting of two relatively movable sections 12 and 13, having overlapping flanges or lips 14 or 15. (See Fig. 5.) Member 12 is stationary, while member 13 is movable for the purpose of expanding and contracting the mouth open-

ing, as hereinafter described. Compartment 6 at its end opposite the section 11 is open.

The end of section 11 which opens into compartment 6 is provided with a flap 6^a having attached to its lower edge a strip 6^b. The purpose of this flap is to press the air out of the bags as they are drawn through the rear end of section 11. A wire screen 5^a prevents the bags from being drawn into compartment 5.

Chamber section 2 is separated by a partition 15, into two compartments or air passages 16 and 17, which open into each other at the rear of said partition, as shown most clearly in Fig. 3. The end of section 2 adjacent section 1 is open, while its other end is permanently closed by a glass window 18. Section 2 also has an opening 19 in its bottom, provided with a leather flap 20 for purposes which will hereinafter more fully appear.

The adjacent edges of sections 1 and 2 are faced, respectively, with felt or other suitable material 21 for preventing the escape of air through said portions when the sections are brought together.

Reciprocating motion is imparted to section 2 by mechanism presently to be described, in such manner as to bring the faces 21 of said sections together and separate them alternately. The bags are placed one at a time with their open ends over the lips 14 and 15 of the mouth of the suction chamber, while the said mouth is contracted, after which the mouth expands and holds the open end of the bag. Suction is constantly applied to outlet 7, so that when the sections 1 and 2 are brought together as stated, an air suction is created through the mouth of section 1 which takes the course of the arrows indicated in Fig. 3, passing out through opening 7. This suction draws the bag in through the mouth of section 11, at the same time turning it and delivering its closed end to compartment 17 of section 2. Immediately after this turning operation, the bag is engaged by a gripper 22 which holds the closed end of the bag down against the bottom of section 2. Directly after this takes place, section 2 is caused to travel away from section 1, and at the proper time

gripper 22 releases the bag and allows it to drop between sections 1 and 2, onto a suitable conveyer hereinafter described.

Reciprocating motion is imparted to section 2 through two rocking levers 23 and 24 mounted at their lower ends upon a rock shaft 25 and connected at their upper ends through rods 26 and 27, respectively, to a shaft 28 which extends transversely through section 2. Yielding connection is effected between levers 23 and 24 and rods 26 and 27 by having said levers act upon said rods through springs 29 and 30, the rods 26 and 27 passing through openings in the upper ends of said levers. Levers 23 and 24 are operated by connecting rod 31 attached to a crank arm 32, fast on a shaft 33, which receives its motion through a gear 34, meshing with a smaller gear 35 on a main driving shaft 36 on which latter is mounted fast a pulley 37 connected by belt 38 with any suitable source of power. Shaft 36 carries also an idler pulley 37' to which the belt may be shifted.

25 The necessary adjustments of the travel of chamber section 2 are effected by adjusting the length of connecting rod 31 and the effective stroke or throw of crank arm 32. For the purpose of adjusting the length of connecting rod 31, it is preferably made in two telescoping sections which may be clamped together in the adjusted position by a set screw 39 or other desired means. For the purpose of varying or adjusting the throw of crank arm 32, connecting rod 31 is attached thereto through a pin and slot connection as shown in Fig. 1.

The gripping device above referred to comprises, among other parts, two arms 40 fast upon shaft 28, and connected by a web 22. This gripping device is operated by the following mechanism: Fast to shaft 28 on the outside of chamber section 2 is an arm 41 having an offset roller 42, in the path of which are located two stationary inclined plane members 43 and 44, attached to the outside of one of the guide supports 4. Member 43 is mounted upon a pivot 43^a. Member 44 may or may not be pivoted as desired. As shown in Fig. 1, chamber section 2 is at about the center of its travel forward or toward section 1. As section 2 proceeds toward section 1, roller 42 travels up the inclined plane of member 43 thereby raising arms 40 and web 22 of the gripping device, and just after sections 1 and 2 come together, roller 42 passes off the forward end of member 43, which allows arms 41 to drop, thereby causing the gripping device to drop onto the forward end of the bag sucked into section 2. As section 2 travels away from section 1, roller 42 of arm 41 travels below member 43, which latter turns on its pivot 43^a to permit the roller 42 to pass and al-

lows the gripping device to retain its hold 65 on the bag. When section 2 approaches the end of its back travel, roller 42 passes onto the inclined plane formed by the upper edge of member 44, thus raising the gripping device and causing the same to release the end 70 of the bag held thereby, which then drops upon the conveyer 45. The other end of the bag is dropped upon said conveyer when it is drawn out of section 1 by the movement of section 2 in its back travel. When 75 the roller 42 passes off the rear end of member 43, it strikes the inclined end of a guide member 43^b which prevents the too sudden dropping of the gripper 22. As section 2 approaches section 1, the bottom edge of an 80 inclined arm 46 fast to section 2 engages the upper edge of a curved pivoted lever 47 on section 1 and forces it down against the tension of a spring 48. Lever 47 being thus actuated, operates upon an arm 49 fast on a 85 shaft 50 on which is mounted a damper 51 within compartment 5. Therefore, when sections 1 and 2 abut, the damper 51 will open compartment 5 to the free passage of air, and when section 2 recedes from section 90 1, the damper automatically closes under the action of spring 48. The closure of the damper in this way prevents the bag from being drawn upward by suction after sections 1 and 2 have separated. The function 95 of opening 19 and flap 20 is to effect a quick break in the suction when section 2 starts on its back travel.

Reverting now to the conveyer, this comprises a belt 45 carried on two drums 52 and 53, the latter of which is mounted upon a shaft 54 to which power is applied, as hereinafter described, to drive the conveyer.

For the purpose of stacking the turned bags on the conveyer, its motion is made intermittent, that is, it remains stationary until a certain number of bags, fifty for example, have been delivered to it one upon the other, and then it moves forward to deliver the stack thus formed. For the purpose of imparting this intermittent motion to the conveyer, the following mechanism is provided: Fast on shaft 54 is a sprocket 55 which is geared through a chain 56 to a sprocket 57 fast on a shaft 58. Also fast on 105 shaft 58 is a clutch member 59, which is adapted at times to engage with a clutch member 60 loose on said shaft. Clutch member 60 is fast to a sprocket 61 which is geared through a chain 62 to a sprocket 63 fast on 110 power shaft 36. Clutch member 61 is slid axially of shaft 58 so as to bring it into engagement and out of engagement with clutch member 59, by a lever 63 fulcrumed as at 64 and operated by two cams 65 and 66 on a face of a gear 67 fast on a shaft 68 and meshing with a worm 69, fast upon a shaft 70, which in turn is driven from shaft 33.

The gearing which drives cams 65 and 66 is so chosen or proportioned, and the cams themselves so arranged, that each time chamber section 2 makes fifty trips, or fifty bags are delivered to the conveyer 45, one of the cams 65—66 will operate upon lever 63 to cause the coupling of clutch members 59 and 60, whereupon the conveyer will be driven a sufficient distance to deliver the stack of bags carried thereby. The conveyer is automatically stopped at the required point by the separation of clutch members 59 and 60, which is in turn effected by the passage of one of cams 65 or 66 from engagement with lever 63, allowing said lever to turn on its fulcrum on the action of spring 71.

Each time a bag is dropped onto the conveyer, it is pressed down thereupon and held by a series of prongs 72 fast on a rock shaft 73. This rock shaft receives its motion through an arm 74 fast thereto and connected to a rod 75 adapted to travel in a guide 76 and to engage the periphery of a cam 77 from which the said rod receives vertical reciprocating motion. Cam 77 is in turn mounted fast upon a shaft 78 which is connected through beveled gears 79 and 80 to shaft 33. Shaft 78 also operates mouth member 13, and for this purpose there is mounted fast on said shaft a cam 81 upon the periphery of which bears one end of a lever 82 fulcrumed on a stud 83 fast to the frame of the machine. Lever 82 is flexibly connected at its upper end to a reciprocating mouth 13. The lower end of lever 82 is held against the periphery of cam 81 under the tension of a spring 84.

The foregoing is a description of one specific form of my invention. This, however, is susceptible to various modifications and changes which may be made within the scope of what I claim.

What I claim is:—

45 1. A bag turning machine comprising a suction chamber having two separable sections each having an open end and said ends facing each other, one of said sections having an outlet for the attachment of an air suction duct and the same section having a mouth through which the bags are drawn in turning, and mechanism to effect relative reciprocating motion between said sections to bring their open ends together and separate them alternately.

50 2. A bag turning machine comprising a suction chamber having two separable sections each having an open end which face each other, one of said sections having an air passage or compartment provided with an outlet for the attachment of an air suction duct, and the same section having another passage or compartment provided with a mouth through which the bags are drawn

in turning, and mechanism to effect relative reciprocating motion between said sections to bring their open ends together and separate them alternately.

55 3. A bag turning machine comprising a suction chamber having two separable sections each having an open end which face each other, one of said sections having an air passage or compartment provided with an outlet for the attachment of an air suction duct, and the same section having another passage or compartment provided with a mouth through which the bags are drawn in turning, mechanism to effect relative reciprocating motion between said sections to bring their open ends together and separate them alternately, a damper in the first mentioned compartment, and mechanism to open said damper when said sections are brought together and to close the same when they are separated.

60 4. A bag turning machine comprising a suction chamber having two separable sections each having an open end facing each other, one of said sections having an outlet for the attachment of an air suction duct and the same section having a mouth through which the bags are drawn in turning, mechanism to effect relative reciprocating motion between said sections to bring their open ends together and separate them alternately, bag gripping means located in one of said sections, and mechanism to cause said means to grip a bag drawn by suction into said chamber when said sections are brought together and to release the bag after said sections have been separated.

65 5. A bag turning machine comprising a suction chamber having two separable sections each having an open end facing each other, one of said sections having an outlet for the attachment of an air suction duct and the same section having a mouth through which the bags are drawn in turning, mechanism to effect relative reciprocating motion between said sections to bring their open ends together and separate them alternately, bag gripping means located in one of said sections, mechanism to cause said means to grip a bag drawn by suction into said chamber when said sections are brought together and to release the bag after said sections have been separated, and a conveyer to receive the bags released by the gripping device.

70 6. A bag turning machine comprising a suction chamber having two separable sections each having an open end facing each other, one of said sections having an outlet for the attachment of an air suction duct and the same section having a mouth through which the bags are drawn in turning, mechanism to effect relative reciprocating motion between said sections to bring

their open ends together and separate them alternately, bag gripping means located in one of said sections, mechanism to cause said means to grip a bag drawn by suction into said chamber when said sections are brought together and to release the bag after said sections have been separated, a conveyer to receive the bags released by the

gripping device, and means to intermittently operate the conveyer. 10

In testimony whereof I affix my signature in presence of two witnesses.

ALBERT NOYES.
